UNITED STATES PATENT OFFICE.

RICHARD T. SGHOLES, OF HINSDALE, ILLINOIS.

TIE PLATE.

Application filed May 6, 1926. Serial No. 107,059.

This invention relates to an improved tie-plate, as used by railroads for supporting the rails upon the wooden ties. The plates prevent the rails from working down into the ties, and also assist the spikes in transferring the lateral thrusts of the rails to the ties and thence to the road-bed.

5 The general object is to provide a simple, efficient and durable plate, in which the material is reduced to a practical minimum without sacrificing any necessary strength or rigidity.

Another object is to provide a tie plate of cantilever design, wherein the material 10 through the central portion of the plate is substantially reduced, and one which will at the same time furnish ample strength and stiffness to resist the tendency of the plate to buckle or bend under load.

20 Another object is to provide a tie plate of the above type having a substantially flat continuous tie-engaging surface.

Another object is to provide a tie plate, the upper surface of which is recessed or 25 hollowed out beneath the rail base, the recessed portion being bridged by a plurality of transverse ribs which assist in supporting the rail base, and are so designed and directed as to most efficiently transmit the 30 lateral thrusts between the two rail-supporting halves of the plate so as to efficiently prevent any buckling or bending of the plate, due to the removal of material through the central zone thereof.

35 Another object is to provide a tie-plate which can be easily and economically rolled, without necessitating any subsequent machining operation except shearing off the plate and punching the spike holes.

40 Other objects and advantages of this invention will be apparent from the following detailed description of certain improved embodiments thereof.

In the accompanying drawings:

45 Fig. 1 is a perspective view of one approved form of the tie-plate.

Fig. 2 is a transverse vertical section through the tie-plate.

50 Fig. 3 is a central longitudinal vertical section, taken substantially on line 3—3 of Fig. 1.

Figs. 4 and 5 are sections corresponding to Fig. 3, showing modifications of the transverse recesses.

55 Figs. 6, 7, 8 and 9 show modified forms of

the tie-engaging rib on the lower face of the plate.

Fig. 10 is a perspective view, similar to Fig. 1, showing a modified form of tie-plate.

Fig. 11 is a transverse vertical section, similar to Fig. 2, through the modification shown in Fig. 10.

Fig. 12 is a view similar to Fig. 11, showing another modification.

Referring first to the form shown in Figs. 1, 2 and 3, the tie plate 1 is of substantially rectangular outline, comprising a relatively thick central rail supporting portion 2, and thinner tapering side flange portions 3 and 4 adapted to extend laterally to some distance at the sides of the rail base to provide an increased supporting area, and to transmit the tilting stresses to the tie. The plate is provided with the usual spike openings 5, through which spikes are driven into the tie to secure the rail and tie-plate to the tie. The plate is also provided with the upstanding shoulder 6, to abut one edge of the rail and transmit the lateral or outward thrust 80 of the rail to the tie-plate.

The lower surface 7 of the plate is substantially flat, to provide a continuous and even tie-engaging surface except for the longitudinal ribs 8 which are to be pressed into the tie to prevent lateral shifting movement between the tie and tie plate. The ribs 8 are preferably rounded, both at their lower extremities and at the sides where they emerge into the bottom 7 of the plate, so as to avoid cutting and damaging the fibres of the tie when the ribs are pressed into the tie by the downward pressure on the tie plate. While the preferred form of rib is shown in Figs. 1 and 2, some possible 95 modifications of this rib are indicated in enlarged sections in Figs. 6 to 9 inclusive. Fig. 7 shows a rib 9 which is downwardly tapered or of triangular cross-section, and is of a type heretofore often used on tie plates.

Fig. 8 shows a rib, the lower portion of which is tapered at 10 and 11 at a much more obtuse angle than the rib 9 shown in Fig. 7, and the upper portions of this rib are rounded, as at 12, to merge into the lower surface of the tie plate. The rib 13 shown in Fig. 6 is quite similar to that shown in Fig. 8, except the lower edge of the rib is flattened or cut away, as indicated 110

at 14. The rib shown in Fig. 9 has a substantially flat lower surface 15, and curved side portions 16 which merge into the lower surface 7 of the tie plate.

5 The upper rail-supporting surface 2 of the plate comprises the parallel continuous side ribs 17 and 18, which support the edge portions of the rail base, and a plurality of transversely extending ribs 19 which extend substantially at right angles to the side ribs 17 and 18. Between the ribs 19 the plate is hollowed out or recessed, as indicated at 20. The primary purpose of these recesses is to decrease the weight or amount 10 of the material in the tie plate, and these recesses and the ribs 19 are so designed that this absence of material does not materially decrease the strength or rigidity of the plate. As indicated in Figs. 1 and 2, these 15 recesses are deepest at their central portions 21, the bottom of each recess curving gradually upward, as indicated at 22, until they merge with the upper surfaces of the rail-supporting ribs 17 and 18. This bottom 20 contour of the recess might differ from that indicated in Fig. 2, that is the recesses might be deeper or shallower toward the ends thereof, it usually being preferable, except 25 as hereinafter noted, that the design be such that the maximum material is removed 30 from the central portions of the plate and the thickness gradually increased toward either side thereof. As indicated in Fig. 3, the bottoms 21 of the recesses are rounded 35 at 23 to merge into the sides of the ribs 19, and the upper edges of the ribs are preferably rounded, as indicated at 24. This rounded construction not only improves the 40 strength of the construction, but also facilitates the rolling operation by which the plate is formed.

Other possible modifications of the transverse cross section of the recesses 20 are indicated in Figs. 4 and 5. In Fig. 4, the recesses are smaller, with rounded bottoms 25, which merge directly into the reverse curves 26 extending into the top of the ribs 19. In Fig. 5, the recesses are larger, having side portions 27 formed much the same as in Fig. 4, but with a flattened bottom 28.

50 In certain prior constructions, the weight of the tie plate has been decreased by hollowing out or recessing the lower surface of the plate, in various manners. The effect of 55 this is to decrease the uniformity of the tie-engaging surface, thus increasing and localizing the wear on the tie and the damage to the tie fibers. Furthermore the plate is so weakened centrally that there is a tendency 60 for the wheel load transmitted through the rail to cause the plate to buckle downwardly at the middle. In other forms of tie-plates, the weight has been decreased by removing material from the upper, rail-supporting 65 portion of the plate, but in such previous

constructions the material has been so removed that the strength and rigidity of the plate have been materially lessened.

The lower surface of the plate is perfectly flat with the exception of the ribs 8 70 extending under and parallel to the edges of the rail base. The ribs are so designed as to avoid cutting the fiber of the tie, and the flat bottom of the plate effects a maximum uniformity of distribution of the pressure 75 on the surface of the tie, and results in a minimum of damage to the tie fiber, at the same time producing what is considered to be ample resistance to the tendency of the tie plate to move laterally on the tie. 80

It will be noted that the body of the tie plate (disregarding for the present the ribs 19) is substantially of the approved cantilever construction. The two halves of the plate are of greatest thickness at the ribs 85 17 and 18 which support the edges of the rail, and each half of the plate tapers in both directions from this main supporting rib, in one direction toward the side edge of the tie plate, and in the other direction toward the thinner central portion 21. On this cantilever body has been superimposed a plurality of transverse ribs 19. These ribs serve two purposes. First, in conjunction with the side ribs 17 and 18, they provide 90 an adequate bearing or supporting surface for the base of the rail. Second, they provide adequate stiffness in the tie-plate as a beam, in order to prevent flexure of the tie plate in the middle under load, and at the 95 same time they relieve the rail base of stresses produced therein in preventing flexure of the tie plate in the middle under load. 100

This design of tie plate produces for a 105 given amount of metal, a maximum strength as a cantilever, and a maximum strength (or moment of inertia) in the middle as a simple beam, as compared with other tie plates now being manufactured and in common use, or as compared with previously proposed tie plate designs. It also produces, for a given size of tie plate, a minimum unit pressure on the surface of the tie, due to the flat unbroken bottom surface and 110 the uniform distribution of pressure. The design, therefore, effects for a given amount of metal a maximum of resistance to flexure under the load transmitted by the rail, and at the same time a minimum of unit pressure on the surface of the tie, thereby reducing damage to the fiber of the tie, due to 115 pressure and uneven application of the pressure. 120

In Figs. 10 and 11 is shown a modified 125 form of the tie plate, these figures being similar to Figs. 1 and 2. Those portions of the tie plate which are the same as previously described in connection with Figs. 1 and 2 will not be again referred to. In 130

addition to the side rail-supporting ribs 17 and 18, this form of the tie plate is provided with a central rail-supporting rib 29, preferably extending substantially parallel to the side ribs 17 and 18. Ribs 18 and 29 are connected by spaced transverse ribs 30, and ribs 17 and 29 are connected by similar transverse ribs 31, the ribs 30 and 31 being preferably continuations of one another and corresponding to the ribs 19 previously described. The recesses 32 between these ribs are substantially the same in all respects as the recesses 20 hereinabove described in detail, except that they are necessarily considerably shorter in view of the closer spacings of the ribs 18 and 29, and 17 and 29. This modified form of tie plate will obviously be somewhat stronger than the form first described, due to the additional supporting rib 29 and the necessarily greater amount of metal used. Otherwise, it will have many of the same advantages claimed for the form shown in Figs. 1, 2 and 3.

If the tie-plate is properly seated on the tie, with the entire lower plane surface in engagement with the flat surface of the tie, the true cantilever construction heretofore described is the preferable design. However, workmen when providing seats for the plates, are apt to "adze" out the tie beneath the plate, that is provide a concave seat so that only the side edges of the tie plate sustain the load, at least until the plate has become imbedded in the tie. In such cases an added strain is thrown on the central portion of the plate tending to buckle it downward in the middle. The plate may be strengthened to resist this central bending pressure by providing the added central rib shown in Figs. 10 and 11, or this construction may be approximated as shown in Fig. 12. In this form the central portion of each transverse recess is made shallower to provide a central longitudinal rib 33, which is not as high as the central rib 29 in Figs. 10 and 11 and does not act as a rail-support, but merely adds strength to the central portion of the plate where the downward buckling might occur if the plate were not properly seated on the tie.

It will be noted that both surfaces of the plate are of such design that the plates can be easily rolled, as a long strip. The finishing operations consist simply in shearing off the plate, and punching the spike holes. The various curves indicated in the drawings may be varied, and the proportions of the plate changed, without departing from the principles of this invention.

I claim:

1. A tie-plate of cantilever construction, the plate having a substantially flat lower tie-engaging surface, and a pair of parallel longitudinally extending rail-supporting ribs on its upper portion, the plate decreas-

ing progressively in thickness from each rib toward the side edges of the plate, and also from each rib toward the center of the plate, and a series of spaced transverse ribs bridging the thinner central portion, and forming additional rail base supporting means. 70

2. A tie-plate of cantilever construction, comprising a pair of parallel longitudinally extending rail-supporting portions so spaced as to underlie the edges of the rail base, the plate gradually decreasing in thickness from each of these rail-supporting portions toward the central portion of the plate and a series of spaced transverse rail-supporting ribs bridging the area of decreased thickness, the ribs extending substantially at right angles to the first mentioned rail-supporting portions. 80

3. A tie-plate having a rail-supporting surface consisting of continuous parallel longitudinal ribs supporting the edges of the rail base, and a series of parallel transverse ribs positioned substantially at right angles to and connecting the longitudinal ribs, the plate between the transverse ribs being recessed, the recesses being deepest at the center and the bottoms curving gradually upward to the level of the longitudinal ribs. 90

4. A tie-plate having a rail-supporting surface consisting of continuous parallel longitudinal ribs supporting the edges of the rail base, and a series of parallel transverse ribs positioned substantially at right angles to and connecting the longitudinal ribs, the plate between the transverse ribs being formed with transversely elongated recesses, the recesses being deepest at their centers, with their bottoms rounded to merge into the sides of the transverse ribs, and curving gradually upwards transversely of the plate to the level of the longitudinal ribs. 100

5. A tie-plate having a continuous flat tie-engaging lower surface, a plurality of substantially parallel rounded downwardly projecting ribs thereon, the upper rail-supporting surface consisting of continuous parallel longitudinal ribs for supporting the edge portions of the rail-base, and a series of parallel transverse ribs positioned substantially 110 at right angles to the longitudinal ribs, the plate being recessed between the transverse ribs, the recesses being deepest at their centers, with their bottoms rounded to merge into the sides of the ribs, and curving gradually upwards transversely of the plate to the level of the longitudinal ribs. 120

6. A tie-plate having an upper rail-supporting surface consisting of three parallel longitudinal ribs, the two outer ribs supporting the edge portions of the rail base, and the third rib centrally supporting the rail, and a plurality of spaced transverse ribs positioned substantially at right angles to and connecting the longitudinal ribs, the 130

plate being recessed between the several ribs.

7. A tie-plate having an upper rail-supporting surface consisting of three parallel longitudinal ribs, the two outer ribs supporting the edge portions of the rail base, and the third rib centrally supporting the rail, and a plurality of spaced transverse ribs positioned substantially at right angles to and connecting the longitudinal ribs, the plate being recessed between the several ribs, the recesses being deepest at their central portions with their bottom surfaces curving upwardly to merge into the longitudinal ribs.

8. A tie-plate of cantilever construction, ¹⁶ having a substantially flat lower tie-engaging surface, and a pair of parallel longitudinally extending rail-supporting ribs on its upper portion, the plate decreasing progressively in thickness from each rib toward ²⁰ the side edges and toward the center of the plate, and a series of spaced transverse rail-supporting ribs bridging the central area of decreased thickness whereby the sustained weight is distributed uniformly to the flat ²⁵ lower surface of the plate to give the minimum unit pressure on the tie.

RICHARD T. SCHOLES.
